Patrick F. Clunk

(57) **CLAIM**

The ornamental design for a weight bar, as shown and described.

DESCRIPTION

FIG. 1 is a perspective view of a first embodiment of the weight bar showing my new design.

FIG. 2 is a front view thereof.

FIG. 3 is a rear view thereof.

FIG. 4 is a top view thereof.

FIG. 5 is a bottom view thereof.

FIG. 6 is a right side view thereof.

FIG. 7 is a left side thereof.

FIG. 8 is a perspective view of a second embodiment of the weight bar showing my new design.

FIG. 9 is a front view thereof.

FIG. 10 is a rear view thereof.

FIG. 11 is a top view thereof.

FIG. 12 is a bottom view thereof;

FIG. 13 is a right side view thereof; and,

FIG. 14 is a left side thereof.

The broken line showing of portions of the weight bar depicts environment and forms no part of the claimed design.

1 Claim, 10 Drawing Sheets
